UNITED STATES PATENT OFFICE.

WILLIAM M. HOERLE, OF ALLEGHENY, PENNSYLVANIA, ASSIGNOR TO
THE PITTSBURGH LAMP AND BRASS COMPANY, OF PITTSBURG,
PENNSYLVANIA.

THREAD-JOINT FOR LAMPS.

SPECIFICATION forming part of Letters Patent No. 651,547, dated June 12, 1900.

Application filed May 10, 1899. Serial No. 716,308. (No model.)

To all whom it may concern:

Be it known that I, WILLIAM M. HOERLE, a resident of Allegheny, in the county of Allegheny and State of Pennsylvania, have invented a new and useful Improvement in Thread-Joints for Lamps; and I do hereby declare the following to be a full, clear, and exact description thereof.

My invention relates to screw-joints for oil and like receptacles. It is a well-known fact that difficulty is experienced in any oil-receptacle, such as lamps or oil cans or reservoirs, from the seeping or leaking of the oil through the screw-joints employed either for the attachment of the burner or the spout for filling the reservoir or, in oil-cans, for the attachment of the pouring-spout. The oil seems to follow by capillary action up along the threads and finally reaches the top of the opening and oozes or seeps out through the joint and spreads over the outer surface of the can. This action often leads to injury to handsome furniture or fittings and is very objectionable. I have found that by the simple device forming the subject-matter of the present invention this difficulty can be overcome.

The invention comprises, generally stated, a joint having above the screw-threads of either member of the joint an inclosed annular recess and grooves extending across the threads or "interrupting" the same, as it might be termed, communicating with such annular recess, it being found that where the oil starts to follow the threads of the joint it is checked either by the grooves formed across and interrupting the threads or that it passes into the recess and passes back through such grooves into the interior of the receptacle, so that all leakage or seepage is overcome.

The particular points of invention desired to be covered will be hereinafter set forth and claimed.

45 To enable others skilled in the art to make and use my invention, I will describe the same more fully, referring to the accompanying drawings, in which—

Figure 1 is a vertical central section of a lamp, illustrating the invention both in connec-

tion with the threaded joint for attaching the burner and the threaded joint for the pouring-hole, the drawing showing the burner-body and the screw-cap closing the pouring-hole in full lines to more fully illustrate the invention. Fig. 2 is an enlarged view of a joint of the character described, showing the two members of the joint together and the two members separate, the upper member in full lines and the lower member in section, to more fully illustrate the invention; and Fig. 3 is an enlarged view showing the filling-opening and above the same the cap for closing it.

Like letters of reference indicate like parts in each view.

My invention may be employed with any suitable form of receptacle for oil or other semivolatile liquid, such as lamps or oil-cans or oil-reservoirs, and also for tubing, where the parts are connected by a flange-joint—that is, where the female part has a flange extending over the top of the male part. As the invention is illustrated in connection with a lamp, to which purpose it is particularly applicable, the lamp-body *a* has formed centrally thereof the usual threaded opening *b* for the attachment of the lamp-burner *c*. Either in the threaded base *d* of the burner or in the threaded opening *b* of the lamp-body, and preferably in both, I form above the threaded portions an annular recess. This recess is marked *e* in the opening *b*, and *f* in threaded base *d*. Above such recess *f* on the threaded base *d* the body of the burner extends out to form the annular flange *g*, which when the lamp-burner is screwed down to place rests on the top edge or shoulder *h* above the threaded opening *b*. It will be seen that in such position the annular recesses *e* and *f* coincide with each other. At suitable intervals in the threads of the opening and base are formed the grooves *k*, two or more of such grooves being preferably employed, though the action desired can be obtained with but one such groove, and it being preferred in large joints to form grooves in the threads both of the opening *b* and the base or male part *d*, though it is found that the joint works well and prevents leakage when such grooves are formed only in one of the members of the

screw-joint. In the joint as so constructed it is found that there is no leakage or seepage of oil whatever, the action being apparently that when the oil attempts to follow around 5 the threads it necessarily creeps in a spiral course to one of the grooves *k*, which directs it downwardly into the interior again, and if any oil does succeed in passing up into the annular recess of the joint formed in either 10 or both members thereof it seems to be unable to rise past such recess to the joint and escape at the top shoulder and the outwardly-extending flange. Whatever the action is, a joint is obtained which overcomes entirely the 15 natural capillary action leading to seepage of the oil found in practically all lamps or oil-receptacles.

The invention can of course be employed with any form of oil-receptacle, whether the 20 threaded opening is formed as part of the same, as shown in Fig. 1, or whether, as in glass or like lamps, it is formed as part of a collar, as illustrated in Fig. 3, where the pouring entrance to such a lamp has a screw-plug 25 for closing the same, as illustrated. In the making of such collars for glass or like lamps the collar is spun up into shape and may either have the recess formed therein and the interrupted thread, as illustrated in the parts 30 shown in Fig. 1, or may be the ordinary ring usually employed, the recess and grooves being formed only in the screw-cap closing the opening. As shown in Fig. 3, this screw-cap *m* has the annular recess *n*, from which 35 grooves *p* extend through the screw-threads, while the body of the cap forms the overhanging flange *r*, which rests on the top of the collar *s*, which is secured by cement to the body of the lamp.

40 The construction illustrated can of course be applied to any screw-joints where the seepage of oil or other semivolatile liquid takes place and which are not subjected to such pressure as would force the oil into the annular recess and keep it filled and by a device which costs practically nothing and can be carried out in the spinning or stamping of the parts with but little or no millwork this dif-

ficulty always experienced in connection with oil-receptacles of the oozing or seeping out of 50 the oil is overcome.

What I claim as my invention, and desire to secure by Letters Patent, is—

1. In a joint for oil or other receptacles, the combination of two threaded joint members, one of said members having one or more grooves extending across the screw-threads thereof, and one member having a flange extending out over a shoulder on the other member, substantially as set forth. 55

2. In a joint for oil or other receptacles, the combination of two threaded joint members, one of said members having an inclosed annular recess formed above the screw-threads and one of said members having one 65 or more grooves extending across the screw-threads, substantially as set forth.

3. In a joint for oil or other receptacles, the combination of two threaded joint members, one of said members having an annular 70 recess above the threads, one member having one or more grooves extending across the screw-threads and one member having a flange extending out over a shoulder on the other member, substantially as set forth. 75

4. In a joint for oil or other receptacles, the combination of two threaded joint members, the threaded members each having an annular recess above the screw-threads thereof, and one of said members having one 80 or more grooves formed across the screw-threads, substantially as set forth.

5. In a joint for oil or other receptacles, the combination of two threaded joint members, one member having a shoulder and the 85 other a flange extending above such shoulder, and each member having an annular recess above the screw-threads and one or more grooves extending across the screw-threads, substantially as set forth. 90

In testimony whereof I, the said WILLIAM M. HOERLE, have hereunto set my hand.

WILLIAM M. HOERLE.
